UNITED STATES PATENT OFFICE.

JOHN T. BON, OF SYRACUSE, NEW YORK.

FOLDING TABLE.

SPECIFICATION forming part of Letters Patent No. 368,055, dated August 9, 1887.

Application filed March 24, 1887. Serial No. 232,215. (No model.)

To all whom it may concern:

Be it known that I, JOHN T. BON, of Syracuse, in the county of Onondaga, in the State of New York, have invented new and useful 5 Improvements in Folding Tables, of which the following, taken in connection with the accompanying drawings, is a full, clear, and exact description.

In said drawings, Figure 1 is an inverted 10 plan view of a folding table embodying my improvements. Fig. 2 is a vertical transverse section on line $\alpha\alpha$, Fig. 1. Fig. 3 is an enlarged detached isometric view of the metallic socket by which the leg is detachably secured 15 to the table-top. Fig. 4 is an isometric end view of one of the legs, and Fig. 5 is a detached plan view of the legs in their folded position.

Similar letters of reference indicate corresponding parts.

My invention relates to the class of tables which have their legs adapted to be folded closely side to side, for convenience of storage or transportation; and my present invention 25 consists in an improved construction and combination of parts, as hereinafter fully described, and specifically set forth in the claims.

In the annexed drawings, T denotes the top of the table, which is a rigid leaf stiffened by 30 the so-called "bed-pieces" $C C$, secured to the under side of said leaf. I do not, however, limit my invention to the use of the aforesaid bed-pieces and the usual side rails on the aforesaid leaf, inasmuch as a plain leaf or 35 board of sufficient rigidity may be removably mounted on the legs.

$l l l l$ represent the legs, which are firmly connected in pairs by two sets of diagonal horizontal cross-bars, $e e$ and $e' e'$, which are 40 rigidly attached at their ends to the upper and lower portions of the legs, and are pivoted radially and in common to a central support consisting of a single vertical bar, o , formed with trunnions on its ends, which trunnions 45 pass through holes in the aforesaid bars $e e e' e'$, in the center of the lengths thereof. Said pivotal support allows the legs to be folded in pairs, closely side by side, as represented in Fig. 5 of the drawings. The upper ends of 50 the legs extend above the upper cross-bars $e e$, and by spreading the legs from each other they

can be brought into proper positions to support the solid top T directly on the ends of the legs, as represented in Figs. 1 and 2 of the drawings. The legs being securely united by 55 the cross-bars pivoted to one and the same vertical pivot-bar, o , renders this structure firm and self-supporting without the aid of the top, and, inasmuch as the top is solid or a single rigid plate, it can be readily mounted on 60 the ends of the legs, and the table can be used for some purposes without fastening the top to the legs. The folding of the table for storage or transportation is also effected with the greatest facility. The attachment of the legs 65 to the top leaf or top frame, when desired, can be made in various ways, and I therefore do not limit myself specifically in this respect. I deem, however, the following devices the best adapted for the purpose. I employ expandable 70 metallic sockets, which are each divided vertically into two sections, a and a' . The section a , I rigidly secure either to the bed-piece C , as shown, or to any other suitable part of the under side of the top leaf or top frame, 75 and the other section, A , which constitutes the cap of the socket, I detachably secure to the stationary section a by a suitable clamp, which is represented in the form of a bolt, i , passing transversely through the socket. 80

In order to better sustain the cap or detachable section on the stationary section I provide both with lugs b and b' , which project from the outer sides of each section at the joints thereof and lap onto the adjacent portion of the other section, as shown in Fig. 3 of the drawings. The leg is secured to the socket by loosening the clamp so as to allow the socket to be distended sufficiently to readily receive the upper end of the leg. Then by tightening 90 the clamp the socket is made to firmly grip the leg and hold the same attached to the table-top.

When the clamp consists of the bolt i , I provide the upper end of the leg with a vertical 95 slot, d , so as to allow the leg to be withdrawn from the socket without necessitating the complete removal of the bolt i ; and in order to compensate for the weakening of the attaching end of the leg by the aforesaid slot I provide the interior of the socket with inward 100 projecting lugs $c c$, which enter the slot d of

the leg when attached, and prevent said portion of the leg from being compressed by pressure of the socket against the sides of the leg when the latter is subjected to lateral strain.

5 I am aware that prior to my invention table-legs have been pivoted in common to a central support; but hitherto either the central support or one set of the legs were permanently attached to the under side of the top of the table and entailed a more complicated and expensive construction, and the legs when damaged or broken are not so readily replaced as in my improved folding table, in which the top is mounted removably on all the legs and free from the central support thereof.

15 What I claim as my invention, and desire to secure by Letters Patent, is—

1. The improved folding table composed of the two sets of cross-bars, *e e* and *e' e'*, pivoted to one and the same vertical pivot-bar *o*, formed at opposite ends with trunnions passing through the aforesaid cross-bars, the legs *l l l l*, rigidly secured to the ends of the cross-bars and extending above the same, and the solid top *T*, mounted removably on the upper ends of the legs, all constructed and combined substantially in the manner specified and shown.

2. In a folding table, the combination of the legs pivoted in pairs and in common to a central support, the top mounted removably on said legs and free from the central support, sockets secured stationary to the under side of the top and adapted to receive the upper ends

35 of the legs, and caps clamped removably on the sides of said ends of the legs, substantially as and for the purpose set forth.

3. In combination with the top leaf or frame, legs secured to the ends of diagonal horizontal cross-bars connected together at their centers 40 by a vertical pivot, vertically-divided sockets secured to said leaf or frame and adapted to receive the upper ends of the legs, and clamps for tightening the socket-sections on the legs, substantially as described and shown.

4. The combination, with the top frame, of the legs *l l l l*, connected together by the horizontal cross-bars *e e* and *e' e'*, the vertical pivot-bar *o*, connected with the cross-bars at the center, and the metallic sockets composed of the sections *a a'*, adapted to receive between them the upper ends of the legs, and clamps for tightening the sockets on the legs, substantially as described and shown.

5. The within-described clamping socket composed of the stationary section *a* and removable section *a'*, provided, respectively, with overlapping lugs *b b'*, and the clamping-bolt *i*, passing transversely through the socket-sections, substantially as described and shown.

Intestimony whereof I have hereunto signed my name and affixed my seal, in the presence of two attesting witnesses, at Syracuse, in the county of Onondaga, in the State of New York.

JOHN T. BON. [L. S.]
